UNITED STATES PATENT OFFICE.

CAMILLE DUQUENNE, OF PARIS, FRANCE.

PULVERULENT-FUEL FURNACE.

Application filed October 10, 1925, Serial No. 61,719, and in France October 27, 1924.

One of the principal difficulties encountered in the operation of pulverulent fuel furnaces is due to the agglomeration and caking of ashes upon the hearth of the combustion chamber which ashes are melted under the influence of the high temperature to which they are subjected. To obviate this caking of the ashes it has already been proposed to use a grate or screen of stationary tubes, 10 cooled by water or compressed air, or a grate of hollow air cooled bars or pipes each made of a single piece. It is proposed to arrange this grate between the combustion chamber and the ash pit, so that the radiation of the 15 heat from the combustion chamber upon the ash pit is entirely or partially eliminated. These arrangements however are attended with serious drawbacks as the deterioration or damage of one tube, due to expansion or 20 any other cause, may result in an interruption of the service, and the failure of such a tube is often the cause of accidents.

The present invention has for its object to eliminate the caking of the ashes upon the 25 hearth of the combustion chamber by means of a particular arrangement of such cooled tubes or conduits whereby the above mentioned drawbacks are eliminated.

The invention essentially consists in installing between the combustion chamber and hearth a plurality of stationary juxtaposed air conduits forming an air screen, and by the provision of means whereby the cooling air may circulate in said conduits, certain special 35 constructive arrangements being provided in said air conduits whereby their supports are protected by refractory covering and their constituent elements may be easily replaced.

The appended drawing shows by way of 40 example an embodiment of the invention, as applied to a multitubular steam boiler. Fig. 1 is a vertical lengthwise section and Fig. 2 a vertical cross section on the line II—II of Fig. 1. Figs. 3 and 4 show the arrangement 45 of an air conduit on a larger scale; Fig. 3 is a lengthwise section of a part of said conduit and Fig. 4 a cross section.

1 is the front wall and 2 the side walls, 3 the fire bridge, 4 the arch, 5 the hearth. The 50 boiler apparatus is diagrammatically represented by its upper drum 6, the lower drum 7, the vaporizing tubes 8 and the return tubes 9, but it is obvious that the boiler may be of any desired type and construction. The combustion takes place in the combustion chamber C by the use of burners employing pow-

dered fuel which are disposed for instance at 10 in the front portion 1. The side walls 2 are cooled by an air circulation to which the air is supplied by the adjustable air inlet gates 13' disposed at the upper part of the said chamber and supplying air through the flues 12 and 12' to the middle and the lower part of the said chamber by means of the ports 11.

According to my said invention, I provide 65 at a suitable distance above the hearth a plurality of air conduits A which in the example are juxtaposed in the parallel position and proceed from the front wall which is provided with an air intake for each conduit, to 70 the fire bridge 3 at which point the air which is heated by its circulation through the said conduits will now pass upwardly through the flues 15, thence flowing by way of the ports 16 to the combustion chamber, the cir- 75 culation being ensured in an adjustable manner through the doors 14 by the vacuum prevailing in the furnace, so that the fire bridge will be cooled and the air which is preliminarily heated can be utilized for combustion 80 purposes while at the same time protecting the upper part of the fire bridge, around which it circulates, from the direct contact with the gas in combustion.

In the present example, the conduits A are 85 constructed as follows: Upon the I beams 17, serving as supports between the front wall and the fire bridge, are disposed the cast iron tubes 18 which are connected together by suitable joints and are employed as air conduits; 90 said tubes are protected by refractory covering members 19 and 20. I provide a simple arrangement comprising cast iron tubes 18 provided at the lower part with the hooked lugs 18'. The members 19 and 20 have such 95 a shape that the lateral members 20 rest at the bottom upon the hooked members 18' and are secured at the upper part by the edges of the upper members 19. The said members can thus be removed and replaced in a simple 100 and rapid manner. Since the cast iron conduits are protected by their refractory coverings and are cooled by the air circulation, they will last for a long time, and on the other hand, the I irons which support the said cast 105 iron tubes will be in contact therewith only at certain points, and are in contact at their entire surface with the circulating air, so that they will also last for a long time.

The cooling grate which is thus formed 110 by the said air conduits will suffice to attain the desired end, which is to constitute a screen

capable of arresting or attenuating the radiation from the combustion region upon the hearth and of preventing the agglomeration of the ash. Should one of the said conduits be damaged, this will occasion no accident nor any stoppage of the boiler or furnace, and when the plant operates in these conditions, at least during a certain time, this will cause no serious inconvenience.

10 Obviously, the air conduits, which are in practice juxtaposed in parallel position with suitable spacing, may be otherwise disposed, and the air may be circulated by other means or by forced circulation; the construction 15 and the support of the said conduits may be modified, as well as the several dispositions and the details of construction, without departing from the principle of the invention.

Claims:

20 1. In a furnace using pulverulent fuel including a device forming an air grate placed between the combustion chamber and the ash pit, a plurality of inner air circulating conduits, refractory elements covering said conduits and carried thereby, each of said conduits comprising a number of interfitting iron sections, and a metallic beam lodged within and supporting each of said conduits, said beam being arranged in such a manner 25 as to be bathed upon its entire surface except the supporting surface by the air circulating within said conduit.

25 2. In a furnace using pulverulent fuel including a device forming an air grate placed between the combustion chamber and the ash pit, a plurality of inner air circulating conduits, refractory elements covering said conduits and carried thereby, each of said conduits comprising a number of interfitting iron 30 sections, a metallic beam lodged within and supporting each of said conduits, said beam being arranged in such a manner as to be bathed upon its entire surface except the supporting surface by the air circulating within 35 said conduit, a fire bridge at the rear of the furnace and provided with flues, the said conduits extending from the front of the furnace into the flues of the fire bridge whereby the upper part of the fire bridge is cooled while

the heat contained in the heated air is 50 recuperated.

3. In a furnace using pulverulent fuel including a device forming an air grate placed between the combustion chamber and the ash pit, a plurality of inner air circulating conduits, refractory elements covering said conduits and carried thereby, each of said conduits comprising a number of interfitting iron sections, a metallic beam lodged within and supporting each of said conduits, said beam being arranged in such a manner as to be bathed upon its entire surface except the supporting surface by the air circulating within 55 said conduit, a fire bridge at the rear of the furnace and provided with flues, the said conduits extending from the front of the furnace into the said flues whereby the upper part of the fire bridge is cooled while the heat contained in the heated air is recuperated, and adjustable inlet means in said conduits to 60 provide access to the said metallic beams.

4. In a furnace using pulverulent fuel including a device forming an air grate placed between the combustion chamber and the ash pit, a plurality of inner air circulating conduits, each comprising a number of interfitting iron sections, flanges provided upon the lower part of said conduits, refractory elements covering said conduits and carried thereby, said refractory elements comprising two lateral parts and a top part, the lateral parts being held in place by the top part and being supported at their lower edges by said conduit flanges, a metallic beam lodged within and supporting each of said conduits, said beam being arranged in such a manner as to be bathed upon its entire surface except the supporting surface by the air circulating within 75 said conduit, a fire bridge at the rear of the furnace and provided with flues, the said conduits extending from the front of the furnace into the flues whereby the upper part of the fire bridge is cooled while the heat contained in the heated air is recuperated, and adjustable inlet means in said conduits to 80 provide access to said metallic beams.

CAMILLE DUQUENNE.
